COMBINED DOOR CHECK AND CLOSER

Filed May 12, 1945

Inventor:

Harold Brown

By F. G. Fischer,

Attorney.

UNITED STATES PATENT OFFICE

2,421,595

COMBINED DOOR CHECK AND CLOSER

Harold Brown, Denver, Colo.

Application May 12, 1945, Serial No. 593,380

1 Claim. (Cl. 16—66)

1

My invention relates to a combined door check and closer, and an important feature of the invention resides in a telescopic piston rod which has a longer movement than the piston head and thereby permits further opening of the door after the piston head has reached the end of its outward movement in the cylinder in which it is arranged.

Other features reside in two separate springs, one of which is weaker than the other and compressed by the piston head as the door is being opened, while the other stretches and permits the door to continue to open to a certain degree after the piston head reaches the end of its forward movement, both springs coacting to check and close the door when the latter is released by the operator.

Other features will hereinafter appear, and in order that the invention may be fully understood reference will now be had to the accompanying drawing, in which—

Fig. 1 is a perspective view of the device connected at one end to a door and at its opposite end to the door casing.

Fig. 2 is a vertical longitudinal section of the device with a modified form of bracket.

Fig. 3 is a rear elevation of the cylinder.

Fig. 4 is a rear elevation of the piston head.

Referring in detail to the different parts, 2 designates the cylinder which is provided at its rear end with an air port 4 controlled by a valve 6. The forward end of the cylinder is closed with a removable cap 8 provided with a reduced forwardly extending tubular portion 10.

The piston head 12 comprises a leather or other flexible cup-shaped member having one or more air ports 14 extending transversely therethrough. The piston head 12 is interposed between a washer 16 and the convex surface of a concavo-convex disk 18, the latter of which is arranged in front of the piston head to control the air ports 14, as will hereinafter appear. The piston head 12, washer 16 and disk 18 have central registering openings to receive a member 20 which is threaded into a member 22. A conical spring 24 is interposed between the disk 18 and cap 8 to move the piston head backward after the door has been opened and released.

The piston rod comprises an inner element 26 and an outer element 28, which latter is telescopically mounted upon the former. The rear end of the inner element 26 is threaded in the axial bore of member 22 and its forward end is provided with a circumferential flange 30 which coacts with an internal flange 32 at the rear end

5

of element 28 in limiting extension of the piston rod.

The outer element 28 extends forward through the tubular portion 10 of cap 8 and is threaded upon a member 34 having a grooved periphery to receive the convolutions at the forward portion of a coil spring 36, the rear end of which is connected to the member 22. The member 34 is threaded upon a member preferably in the form of a screw eye 37 connected at its outer end to an eye 38 projecting from the door A.

The forward end of the member 34 is provided with an ornamental cap 40 which overlaps the forward end of the coil spring 36 and has a reduced forward portion 42 of angular form to snugly fit upon the correspondingly shaped reduced forward end of member 34, so that it may be rotated upon the screw eye 37 by a wrench to tension the coil spring 36. A jamb nut 44 is threaded upon the screw eye 37 for engagement with the forward end of the member 34 to prevent accidental turning thereof upon the screw eye.

The rear end of the cylinder 2 is connected by suitable means to the door casing B. In Fig. 1, I have shown such means in the form of a bracket 46 and a link 48 pivoted at its respective ends to the bracket 46 and a pair of lugs 50, which latter are fixed to the rear end of the cylinder.

Fig. 2 discloses another form of means for connecting the cylinder to the door casing, in which a coil spring 52 is employed to coact with the springs 24 and 36 in closing the door. The upper end of the spring 52 is secured to a tubular bracket 54 and its lower end to a crank 56 extending outward through a slot 58 in the bracket 54 and pivotally connected to the lugs 50. The crank 56 is fixed to the lower end of a vertical shaft 60 which is journaled in the bracket 54 and threaded or otherwise secured at its upper end to a disk 62 freely mounted in the recessed portion 64 of the bracket, which latter is provided at its lower end with a removable cap 66 to permit assembly of the parts therein.

Operation.—When the door is being opened the spring 36, which is stronger than spring 24, moves forward with the piston rod and pulls the piston head 12 therewith, thus compressing spring 24. During the first part of the movement spring 36 is stretched very little, but the resistance of spring 24 increases until the piston rod element 28 moves faster than the element 26 and thus stretches spring 36 to an appreciable extent. After the piston head reaches the forward end 55 of its movement opening of the door may con-

tinue due to the stretching of spring 36 until the door is either released by the operator or forward movement of element 28 is checked by the flange 32 contacting flange 30. When the door is released by the operator the spring 24 moves the piston head backward to close the door, which operation is assisted by contraction of the spring 36.

During backward movement of the piston head the air pressure against the same flexes it against the disk 18 which closes the ports 14 and thus entraps the air between the piston head and the rear end of cylinder 2. The entrapped air escapes slowly through port 4, but retards backward movement of the piston head sufficiently to prevent the springs 24 and 36 from slamming the door against the usual stops on the door casing B. The spring 52, which is tensioned by opening of the door, coacts with the springs 24 and 36 in closing the door. If the door is equipped with a lock having the customary spring latch a portion of the air entrapped between the piston and the rear end of the cylinder is permitted to escape into the forward portion of cylinder 2 through a bypass 10 before the piston reaches the end of its backward movement. This reduces the pressure on the piston head and permits acceleration thereof sufficiently to overcome the spring latch and completely close the door. If the door is of the swinging type without a spring latch the bypass 10 may be dispensed with.

From the foregoing description it is apparent that I have provided a door check and closer which is well adapted for the purpose intended, and while I have particularly described elements well adapted to perform the functions set forth, it is obvious that various changes in form, pro-

portion and in the minor details of construction may be resorted to without departing from the spirit of, or sacrificing any of the principles of the invention.

Having thus described my invention, what I claim and desire to secure by Letters Patent is:

A device for checking and closing a door comprising a cylinder having an opening in its front end, means for connecting the rear end of said cylinder to the door casing, a piston rod reciprocably mounted in the cylinder and projecting through the opening in the front end of the cylinder, means for connecting the outer end of the piston rod to the door, a concavoconvex disk secured to the rear portion of said piston rod and positioned with its convex surface to the rear, a flexible piston head secured to the piston rod and provided with one or more air ports adapted to be closed by flexing of the piston head against the convex surface of the disk on each backward stroke of said piston head, a washer secured to the piston rod and abutting the rear surface of the piston head, and spring means interposed between the concave surface of the disk and the front end of the cylinder.

HAROLD BROWN.
